DESIGN.

J. L. GOBEILLE.

HEATING STOVE.

No. 18,731.

Patented Nov. 13, 1888.

UNITED STATES PATENT OFFICE.

JOSEPH LEON GOBEILLE, OF CLEVELAND, ASSIGNOR TO A. T. NYE & SON,
OF MARINETTA, OHIO.

DESIGN FOR A HEATING-STOVE.

SPECIFICATION forming part of Design No. 18,731, dated November 13, 1888.
Application filed September 6, 1888. Serial No. 284,704. Term of patent 7 years.

To all whom it may concern:

Be it known that I, JOSEPH LEON GOBEILLE, a citizen of the United States, residing at Cleveland, in the county of Cuyahoga and 5 State of Ohio, have invented and produced a new and original Design for Stoves; and I do hereby declare that the following is a full, clear, and exact description of the invention, which will enable others skilled in the art to 10 to which it appertains to make and use the same.

The design embraces new and distinctive parts and combinations of parts, as herein-after specified, and shown in the photograph.

One part of the design is found in the shape 15 and ornamentation of the skirting A of the base, the same running in gracefully-curved lines, as shown, from the legs to the center, where they curve upward and are lost behind a rosette set with rounded edge and border 20 partly exposed below the skirting on either side. The skirting throughout its length swells out somewhat from its top to its lower edge, corresponding in a measure to the swell of the legs A'. At its center is a rosette, a, 25 surrounded by small hemispheres connected by a string, and similar ornamentation runs along the lower edge of the skirting from the center rosette to the feet. On either side of this rosette is represented a dogwood-blossom 30 with leaves, and beyond these, running to the foot, is a scroll. The center of the leg is figured the same as the center of the skirt, with field of small blossoms arranged as groundwork.

The base B of the stove has a string ornamentation consisting of three layers of wavy 35 outline on the top, immediately above which is a band of leaves and blossoms inclosing the name of the stove and the place of manufacture, which are cast in ornamental letters with 40 the skirting above described.

Another part of the design is found in the shape and ornamentation of the upper portion 45 of the front of the stove, where the band C on the bottom of the hood C' is seen as extending across the pilasters D on either side, and is raised slightly above the surface of the same, as shown at the corner e, thus conveying to the eye the appearance of massiveness, which, with the swell e' of the hood, serves to give a 50 pleasing effect and contributes materially to the style of the stove. The ornamentation of

the center of the hood is the same as that of the skirt, with a panel on either side having a scroll within disposed in a pebbled background. At either side and above the panel 55 is a groundwork of blossoms. At their base the pilasters have an ornamentation of three beads set crosswise in X shape, with a small rosette in each angle. Along their body is the prevailing ornamentation of dogwood 60 blossoms and leaves arranged on a pebbled background, and at the top, above the crossing band C on each pilaster, is a single acanthus-leaf set vertically.

The top of the stove, E, has a rounded outer 65 edge with ornamentation consisting of vertical pieces of triangular section disposed alternately in equal lengths. The horizontal portion of the top has scroll-work with blossoms. Growing out of this surface and showing on 70 the inclined side of the top is ornamentation with interspersed spear and dart at regular intervals.

The swinging cover F on the top of the stove has a band ornament around its lower portion, 75 consisting of round plates alternated with darts. Above this is a beaded boundary with fretwork disposed in squares, in the center of which is a rounded platform, on which the urn is supported.

Another part of my design relates to the shape and ornamentation of the draft-door G, in which three circular draft-openings, g, are disposed in a line along the bottom part of the door and two other similar openings occupy a 85 position above and between the three lower openings, while a series of windows, g', of rectangular outline, occupy the upper part of the door. A small rosette with raised circular border is set between the opening g and leaves 90 about the same, as shown.

Another part of my design relates to the shape and ornamentation of the foot-rail K, which has an inward projection at its center k, formed by lines curving gradually outward 95 from the straight portion of the rail on either side of the projection. The ornamentation consists in a series of A-shaped figures set side by side on the surface of the rail, with leaves 100 decorating the space within and between the said figures.

The blower L is ornamented by a row of ro-

settes set in a pebbled background surrounding and overlapping the squares of mica.

The whole design is comprised in the shape and ornamentation of the several parts hereinbefore described.

Having thus described my invention, what I claim as new, and desire to secure by Letters Patent, is—

1. In a design for a stove, the shape and ornamentation of the draft-floor, comprising a series of three openings in a line and two other openings disposed above these and intermediate of the space between the same, spaces for mica in a line above said openings, and the ornamentation about said openings, as shown and described.

2. In a design for a stove, the shape and ornamentation of the foot-rail, said rail having an inward projection at its center and gradually tapering lines extending back therefrom to the straight portion of the rail, and ornamented with A-shaped figures and leaves, as shown and described.

3. In a design for a stove, the ornamentation of the pilaster, the same consisting in dogwood flowers and leaves along the body part, crossed beads and rosettes at the bottom, and an acanthus-leaf at the top, as shown and described.

30 4. In a design for a stove, the shape and ornamentation of the blower, consisting in the outward swell of the body, with a series of mica squares and a row of rosettes encircling the mica squares, as shown and described.

35 5. In a design for a stove, the shape and ornamentation of the top, the same being rounded

at the corners and having vertical bars of unequal length disposed alternately on the edge, with scroll-work and blossoms on the horizontal portion, and spear and dart figures shooting out of this surface on the inclined side of the top, as shown and described.

6. In a design for a stove, the shape and ornamentation of the legs, the same decorated centrally with a rosette, with less conspicuous ornamentation on either side of said rosette and rounded outwardly from the top, as shown and described.

7. In a design for a stove, the shape and ornamentation of the hood, consisting of a rosette in the center, a panel with scroll-work on either side of the rosette, and blossoms disposed above and at either side, with the outward bulge of the hood, as shown and described.

8. In a design for a stove, the shape and ornamentation on the base, consisting of layers of wavy outline along the top surface, a band of leaves and flowers within the said wavy outline, and having its front skirting swelling outward and ornamented with a rosette, leaves, and a scroll, as shown and described.

9. The design for a heating-stove herein shown and described, consisting of the base A, the legs A', the base B, the hood C, the pilasters D, the top E, the swinging cover F, the draft-door G, the floor-rail K, and the blower L, all shaped and ornamented as shown and described.

JOSEPH LEON GOBEILLE.
